UNITED STATES PATENT OFFICE.

JOHN ALLEN HEANY, OF YORK, PENNSYLVANIA, ASSIGNOR TO THE HEANY LAMP COMPANY, OF NEW YORK, N. Y., A CORPORATION OF MAINE.

PISTON-VALVE.

960,912.

Specification of Letters Patent. Patented June 7, 1910.

Application filed April 16, 1909. Serial No. 490,269.

To all whom it may concern:

Be it known that I, JOHN ALLEN HEANY, a citizen of the United States, residing at York, in the county of York and State of Pennsylvania, have invented certain new and useful Improvements in Piston-Valves, of which the following is a specification.

This invention relates to a piston valve particularly adapted for use in a vacuum system, such as is used for exhausting incandescent lamp bulbs, and has for its object the production of a valve, which will absolutely prevent leakage of air into the system.

Referring to the accompanying drawings:—Figure 1 is a sectional elevation of the valve; and Fig. 2 is a plan view.

As shown in the drawings 2 is a casing within which is contained a piston valve 3. At the lower end of this casing is an accurately fitted flanged plug 4, secured to the casing by a soldered joint 5. Extending through the plug and an upward extension 6 thereof is a passage 7. Screwed into a registering opening in the bottom of the plug is a pipe 8, also having a soldered joint 9, by which leakage is prevented at that point. Surrounding the extension 6, is an annular ridge 10, having its edges beveled to an edge, the so-formed comparatively sharp edge being arranged to coöperate with an annular rubber packing 12, set into the bottom portion of the piston 3. This piston is provided with a recess 14, into which the extension 6 projects. Extending downwardly into this recess 14, is a pin 15, of such a diameter as to snugly fit into and thus close the passage 7 in the extension 6. This pin extends downwardly from the top of the recess 14, to such a distance that passage of air through the conduit 7 is, in closing the valve, cut off slightly in advance of the engagement of the lower edge of the valve with the mercury 16. By this arrangement of parts, the mercury, 16, placed in the bottom of the valve chamber 17 is prevented from being blown or carried over into the passage 7.

The mercury in the chamber is of such depth that when the piston-valve is fully closed, it will rise above the plane of the meeting parts, and thus afford an additional seal.

The piston-valve is carried by a piston-rod

18, which is operated by means of a lever 55 19, having a handle 20, having therein a slot 21, through which passes a curved arm 22, pivoted to the top plate 23, and normally pressed outwardly by the spring 24. The arm 22 has a finger-piece 220 and a lug 25 60 adapted to engage with either the top or bottom face of the arm 20 and thus hold the valve open or shut.

To the top of the casing 2 is screwed a cap 30 to which are secured by any desired 65 means, the top plate 23, and the block 31, in which is mounted the spring 24, and which is provided with a handle 32, complementary to the handle 20. The upper end of the main valve chamber 17, is closed 70 by a stuffing-box 33, screwed into the casing 2, and having an external screw thread 35 and flange 34 provided with holes 36 to receive a suitable wrench. Surrounding the piston-rod is a suitable packing 37, such as 75 wicking soaked in hot tallow, which is compressed by means of a ring 38, which is in turn held down by an externally screw-threaded hollow shell 39, which is screwed down through the top-plate 23 and cap 30, 80 its inner bore forming a guide for the piston-rod.

The chambers 40, 41, formed in the upper part of the casing and within the shell 39 communicate by means of openings 42 and 85 are filled with mercury to the level indicated.

An inlet pipe 43 leads to the bulbs or other chamber to be exhausted.

Supporting bands 50 are arranged to suitably support the valve mechanism.

60 is an opening through which mercury may be introduced into the upper chamber.

It will be noted that the stuffing-box constitutes a diaphragm for dividing the hollow 95 casing into an upper sealing chamber, and a lower valve-chamber, in each of which is provided a mercury seal, in addition to the other devices, which are in themselves adapted to form air-tight closures at the necessary 100 points.

I claim:

1. A valve mechanism comprising a hollow casing having formed therein a chamber provided with inlet and exit openings, a valve seat and a valve engaging therewith, a closure for such chamber provided with a packing device for the valve rod, a cap for

the casing through which the valve rod passes and mercury seals in the valve chamber and about the valve rod.

2. A valve device comprising a hollow casing divided by a stuffing-box into two closed chambers, a valve in the lower chamber, and a valve rod extending through the stuffing-box and upper chamber, said upper chamber being adapted to receive a mercury seal.

10 3. A valve device comprising a hollow casing divided by a stuffing-box into two closed chambers, a valve in the lower chamber, a rod extending through the stuffing-box and upper chamber, and a mercury seal in each chamber.

4. A valve mechanism comprising a valve and its coöperating seat, and a supplemental closing device carried by the valve and arranged to effect a closure in advance of that effected by the valve.

5. A casing having a chamber therein, a valve-seat therein, a coöperating valve, an upwardly extending conduit, a closure for said conduit carried by the valve, the parts being so proportioned that the closure is effected before the valve reaches its seat.

25 6. In an air valve mechanism, a casing having a chamber therein, an exit opening

in the bottom thereof, an annular valve-seat surrounding said opening, an annular chambered valve and packing arranged to coöperate with the seat, a tube extending upwardly from the opening into the chamber, and a plug in the roof of the chamber for closing the tube.

35 7. A valve casing having an upper and lower chamber of different diameters, a stuffing-box screwed into the upper end of the lower chamber, an apertured hollow shell screwed into and through the top of the upper chamber and engaging the stuffing box, and a valve rod passing through the shell and stuffing-box, and a valve carried by said rod and located in said lower chamber.

8. A valve casing, a piston valve therein, a valve rod, an operating lever connected to the valve-rod, and a spring pressed catch arm, arranged to engage the lever and hold the valve in either its open or closed position.

45 In testimony whereof, I affix my signature 50 in presence of two witnesses.

JOHN ALLEN HEANY.
